UNITED STATES PATENT OFFICE

2,570,767

WOOL COMBING MACHINE

William E. Christensen, Auburn, and William B. Smith and James J. Sandy, Worcester, Mass., assignors to James Smith & Son, Inc., Worcester, Mass., a corporation of Massachusetts

Application May 2, 1950, Serial No. 159,588

7 Claims. (Cl. 19—123)

1

This invention relates to new and improved wool combing machines, particularly of the Noble type, these machines being relatively large and heavy in construction and embodying a large pin circle and two small pin circles, in cooperation with a vertical high-speed reciprocating brush, preparing the wool for combing as disclosed in Patent No. 1,845,351, February 16, 1932, this patent disclosing improvements in the roll adjustment; and attention is also directed to Patent No. 1,026,058, May 14, 1912, for further disclosures of prior art machines of the type herein referred to.

In the prior art it has been customary to drive the above referred to brush by outboard means adjacent the circumference of the large pin circle from an overhead driven shaft, the latter in turn being driven from a main shaft and having a belt shifter approximately at the center of the large pin circle and above the same whereby the operator is forced to stop and start the machine by leaning over the mechanism of the machine in order to grasp the belt shifter; also prior art machines have been cumbersome and hard to service due to the relative complexity and sturdiness required in a machine of this type, and it is a principal object of the present invention to clearly improve and at the same time simplify the driving mechanism for the pin circles, the rolls and the brushes, at the same time greatly increasing the speed of the machine and the output thereof while at the same time observing and retaining the advantages derived in the inventions disclosed in the above referred to patents.

Further objects of the invention include the provision of improved means for lifting the upper portions of the driving means without disturbing the lower portion of the machine or any parts of the wool combing apparatus; the provision of improved means for driving the brushes so as to greatly facilitate servicing, assembly, etc., thereof; and the provision in general of improved driving means for a wool combing machine of the class described.

Other objects and advantages of the invention will appear hereinafter.

Reference is to be had to the accompanying drawings in which

Fig. 1 is a top plan view of a combing machine according to the present invention, parts being omitted for clarity;

Fig. 2 is a view in elevation of the upper part of the combing machine, parts being in section;

Fig. 3 is a section on line 3—3 of Fig. 2; and

Fig. 4 is a section on line 4—4 of Fig. 3.

The combing machine of the type disclosed

2

herein comprises a base generally indicated at 10, this base being circular and relatively heavy as it carries the entire combing mechanism, driving means, etc. Adjacent the periphery thereof 15 the base 10 carries a circular ball race 12 on which is rotatably mounted a large pin circle plate 14 and as is well known the large pin circle plate 14 rotates at a relatively slow speed on the base 10 in substantial tangency to a pair of small pin circle plates 16.

Appropriate driving means is arranged to drive these plates at the same circumferential speed, this driving means being largely below the top surface of the base 10, i. e., below the web or 20 base top 18 of Fig. 2. Such driving means is conventional and well known and illustrated in Fig. 1 by the broken lines which illustrate gears 20, 22, 24, 26, 28. These gears form a gear train from gear 30 on the main shaft 32 for driving the large and small pin circle plates and the 25 wool combing rollers, which rollers are more particularly described in the above identified Patent No. 1,845,351. It is to be noted that the two main shafts 32 are alike and the two small pin circles are duplicates and each performs the same operation as the other, doubling the capacity of the machine. Theoretically it would be possible to go on multiplying these small pin circles to increase the capacity of the machine, but practically such a scheme does not work 30 out, it having been found that the double pin circle arrangement is the best.

Wool combing roller 34 is driven by gear 28 and the gear 24 drives a pair of gears 36 each separately driving a spur gear 38, 40 respectively, 35 the latter driving the large pin circle plate 14, the gear 38 driving the small pin circle plates 16. The above description shows briefly the complete driving means for the machine except for the brushes to be described below; but the brush 40 drive is above the table top 18 whereas the remainder of the machine drive is below the latter, and this invention has to do mainly with the driving mechanism above the table top 18.

Each small pin circle plate 16 is mounted to 45 rotate on a stationary support 42 which may be bolted to the table 18, and inside the support 42 which is preferably circular, a column or pillar 44 is bolted to the table top as by a flange 46. The pillar 44 receives the top end of shaft 32 50 which terminates adjacent the flange in a clutch member 48. A corresponding clutch member 50 is fixed to the bottom of a vertical shaft 52 rising within the pillar and journaled as shown in Fig. 3 terminating in a worm wheel 54. This worm wheel is engaged by a worm 56 on a cross

shaft 58 journaled in the sides of a box 60, the latter being mounted on and forming a part of the pillar 44.

Shaft 58 extends out of the box in a general direction inwardly toward the central axis of the entire machine and is provided with a pulley 62 over which is trained a belt or belts 64 running up to a pulley 66 on the drive shaft of a motor 68. All of this mechanism is duplicated as at the other end of the motor and like reference numerals have been applied to like parts thereof.

The worm shaft 58 is provided with a pulley or sprocket 70 driving another shaft 72, shaft 72 likewise being journaled in the box 60 parallel to shaft 58 and extending outwardly of the box 60 oppositely to the extent of shaft 58, terminating in a clutch member 74. Cooperating with clutch member 74 there is a separable clutch member 76 mounted on a shaft 78, the latter being journaled in a detachable plate 80 having flanges bolted as at 82 to the pillar 44 which extends above the box 60 as at 84. Thus it is seen that the base 80, shaft 78 and clutch part 76 forms an attachment which is easily dismounted from the machine for servicing, repair, and inspection, etc., and it is to be particularly noted that the drive means for shaft 78 is completely "inboard" relative to the pin circles so that the drive therefor is completely protected and the operator of the machine is protected therefrom. This particular drive clearly improves and makes more positive the prior art outboard belt driven mechanisms used heretofore.

Shaft 78 may be provided with a fly wheel 85 if desired, but in any case, the main purpose of shaft 78 is to vertically reciprocate the brush 88 which is shown in down position at the right side of Fig. 2 and in up position at the left side thereof, this brush being positioned just above the tangent point of the large and small pin circles, which tangent points are indicated at 90. Any mechanism desired or convenient may be utilized to reciprocate the brush from shaft 78 and in the present case a counter-weighted cam crank 92 is utilized for this purpose. All of the mechanism for the brush drive is mounted in a housing 94 in turn mounted on the plate 80 so that the entire brush mechanism forms a single unit easily attached and detached from the pillars 44.

The motor 68 is mounted on a bridge 96, the same being supported at its ends on the boxes 84 which form the uppermost parts of pillars 44 and this construction provides a strong and rigid mounting for the motor, the gearing and the brushes. At the tops of boxes 84 there are provided pivoted rings 98 on pins 100 which rings may be utilized for the attachment of cables so that the entire drive mechanism above table 18, with the exception of the pin circles, is easily elevated upon removal of the bolts holding flanges 46 to the table 18.

In the operation of this machine, the boxes 102, see Fig. 1, guide the wool in ropes to the pins 104 of the large pin circle and the brushes 88 pound the wool down into the pins at the tangential point 90 so that the wool combing rollers 34 may perform the combing function in the usual manner.

The present invention provides a positive drive for all the parts of the machine, such drive having been clearly simplified over the prior art and made much easier to control by reason of the new driving mechanism including the electric motor; the new drive mechanism has resulted in the capability of the machine to be driven at a much

higher speed without vibration and the drive is better protected from the entrance of dust and dirt than in the prior art.

The present invention also provides a machine in which the drive parts are largely housed with the exception of belt 64, the latter however being well within the confines of the machine and in fact approaching the center thereof where it is not necessary for the operator to extend his hands due to the fact that the motor 68 is easily remotely controlled; most of the driving parts may run in oil and the machine is longer lasting and runs longer and faster and with less vibration without the necessity of being taken down or serviced in any way.

Having thus described our invention and the advantages thereof, we do not wish to be limited to the details herein disclosed otherwise than as set forth in the claims, but what we claim is:

1. A machine of the class described comprising a base, a pair of upright pillars on said base, driving means within the pillars extending into the base, a bridge connecting the pillars and supported thereon, a motor on the bridge, driving means from the motor to both pillars separately, a detachable bracket on each pillar, a reciprocating brush on each bracket, a shaft in each bracket for driving the brush, a clutch member on said shaft, and a cooperating clutch member operatively arranged on each pillar for engagement therewith.

2. In a combing machine, the combination of a large pin circle plate, a pair of small pin circle plates cooperating therewith, a base therefor, a pillar for each small pin circle plate arranged on the base and rising upwardly therefrom, a shaft in each pillar, said shafts extending only part way the length of the pillars, means to drive said shafts, a bridge extending between said pillars and connecting the same, an electric motor on the bridge, driving means from the motor to each said shaft driving means, a brush for each shaft, and separate means driving the pin circles and brushes from said shaft driving means.

3. A combing machine comprising a base, a large pin circle thereon, a small pin circle cooperating with the large pin circle, a pillar, driving means in the pillar, means to drive the pin circles therefrom, an extending shaft on the pillar, a clutch member on the extending end of said shaft, a brush attachment, means to detachably secure the same to the pillar, a shaft in the attachment, and a clutch member thereon to cooperate with the first named clutch member, said attachment being located to present the brush to the pins of the circles.

4. A combing machine comprising a base, a large pin circle thereon, a small pin circle cooperating with the large pin circle, a pillar, driving means in the pillar, means to drive the pin circles therefrom, an extending shaft on the pillar, a clutch member on the extending end of said shaft, a brush attachment, means to detachably secure the same to the pillar, a shaft in the attachment, and a clutch member thereon to cooperate with the first named clutch member, said attachment being located to present the brush to the pins of the circles, a platform on the pillar, a motor on the platform, and means driving the extending shaft from the motor.

5. A combing machine comprising a base, a pair of spaced pillars thereon and rising therefrom, a bridge connecting the pillars, a motor on the bridge and supported thereby, a cross

shaft in each pillar, means to drive the shafts from the motor, a vertical shaft in each pillar driven by the cross shaft, and combing devices driven by said vertical shafts.

6. A combing machine comprising a base, a pair of spaced pillars thereon and rising therefrom, a bridge connecting the pillars, a motor on the bridge and supported thereby, a cross shaft in each pillar, means to drive the shafts from the motor, a vertical shaft in each pillar 10 driven by the cross shaft, combing devices driven by said vertical shafts, a brush, a second cross shaft driven from the first named shaft, and means driving the brush from the second named cross shaft.

7. A machine of the class described comprising a base, a large pin circle, a pair of small spaced pin circles disposed within the large pin circle and tangent thereto, a pair of pillars on the base each rising therefrom within a small pin circle, a cross shaft in each pillar having

their axes in general extending approximately toward the central vertical axis of the base, a bridge on and connecting the pillars and supported thereon, a motor on the bridge, means driving the shafts from the motor, said means being located at the sides of the pillars facing toward said axis, and shafts in the pillars driven by said means.
